UNITED STATES PATENT OFFICE.

LAFAYETTE T. BOW AND DOCTOR B. VERNON, OF ARDMORE, OKLAHOMA.

BURIAL-CASKET.

1,075,086.

Specification of Letters Patent.

Patented Oct. 7, 1913.

Application filed January 14, 1913. Serial No. 741,936.

To all whom it may concern:

Be it known that we, LAFAYETTE T. Bow and Doctor B. VERNON, of Ardmore, Carter county, Oklahoma, have invented certain new and useful Improvements in Burial-Caskets; and we hereby declare that the following is a full, clear, and exact description thereof, reference being had to the accompanying drawings, which form part of this specification.

This invention is a novel improvement in caskets, coffins, and sarcophagi; and its object is to provide a metal and concrete casket which may be hermetically sealed so as to exclude air and water; and which will be particularly useful in places where, on account of the crowded condition of the cemetery, it is necessary to make successive interments in the same grave.

The invention in particular is an improvement on the casket shown in Patent 1,043,664 dated November 5, 1912, and the object of the present invention is to simplify the construction of said coffin and to facilitate the sealing thereof, and produce a symmetrical and handsome casket, and at the same time reduce the weight thereof as compared with that shown in said patent.

We will explain the invention with reference to the accompanying drawings which illustrate one practical embodiment of the invention, and refer to the claims for summaries of the novel parts and features of the invention for which we desire protection.

In said drawings—Figure 1 is a part side elevation and part longitudinal section of a casket constructed in accordance with our invention. Fig. 2 is a part transverse section and part end elevation of such casket. Fig. 3 is a detail sectional view; and Fig. 4 is a detail perspective view of the cover catches.

The casket body is formed of a metal box 1 of the desired size and shape, open at top but closed at its ends, sides and bottom. Around this box, near the upper edge thereof, is a flange 4^a which may be formed of a strip of sheet metal bent longitudinally in triangular form, in cross section, so as to have a flat upper surface 4^b perpendicular to the vertical sides of the box. This flange may be formed on or secured to the box by soldering, riveting or in any other desired manner, and is arranged a little below the top edge of the box, which projects above

the top surface 4^b of this flange, as indicated at 1^a; this portion 1^a forming a collar above the flange, which collar is adapted to fit into the cover hereinafter referred to, 60 and form a close joint therewith.

Preferably around the box 1 at the base of the flange 4^a to the outside thereof we attach a wire 1^c, which is used as a support for wires 2 that extend from beneath the 65 flange at one side of the box down on the outside of the box and beneath it to and up on the other side of the box to the wire 1^c; and similar wires 1^a extend from the wire 1^c at one end of the box down beneath the box 70 and up at the other end thereof to the wire 1^c, as indicated in the drawings. These wires 2 and 1^a intersect beneath the box and are used as an economical means to hold a wire netting 3 away from the outer surface of 75 the box 1, which netting is placed over and attached to the ends, sides and bottom of the box, as indicated in the drawings, being spaced away from the outer surfaces of the box 1 by the wires 2 and 1^a so that when 80 the exterior coating C of cement is applied to the box the wire netting will be embedded in such cement, as indicated in the drawings. The wire netting 3 may be bent to form a cylinder, indicated at 3^a, beneath 85 the flange 4^a, and the ends of the wires 2 and 1^a may be bent around this roll 3^a of netting as indicated at 2^a Fig. 2, and 1^b Fig. 1 in the drawings, to hold this cylinder 3^a in place while the cement is being 90 applied. Preferably the cement coating extends to the top of the roll 3^a, as indicated in Fig. 2, and the flange 4^a projects above the top C' of the cement coating. The cement covering cylinder 3^a produces an ornamental 95 cement bead or shoulder C^a on the box beneath the flange 4^a as shown.

The cover 5 of the box is preferably hollow and is made of metal, corresponding in width and length, but not in depth, to the 100 box 1; said cover 5 is adapted to fit over the collar 1^a when placed upon the box, as shown in Fig. 1, and it has on its lower edge a horizontal projecting flange 5^b which is adapted to rest upon the flat top surface 105 4^b of the flange 4^a and form a close joint therewith. The parts 5^b and 4^a being of metal and fitting close together, when the coffin is to be sealed these parts can be soldered together and thus hermetically close 110 the box and attach the cover permanently to the body.

The cover 5 is preferably exteriorly covered with wire netting 8 and then with cement as indicated at C³, so that the netting will be embedded in the cement. The netting may be positioned on the top of the cover by means of longitudinally disposed ribs 6, 6^a which may be formed of metal; and the central rib 6 is preferably higher than the side ribs 6^a so as to give a sloping or convex shape to the top of the cover. These ribs 6, 6^a stiffen the cover longitudinally and it may be also stiffened transversely by means of metallic pieces 5^c attached to the under side of the top of the cover as shown. The interior surfaces of the box and cover may be lined with any suitable material, or may be coated with white enamel, or given any desired interior finish. The top is to be covered with cement except the projecting portion of flange 5^b as indicated in Fig. 2; and the body or box is to be covered with cement except the collar 1^a and upper part of flange 4^b as indicated in Fig. 2; and when the interiors of the body and cover are properly finished, the casket is ready for use; and is to be kept in stock and sold in such condition.

After a corpse has been placed in the box 1 the cover 5 is placed thereover so that the metallic flange 5^b rests upon the metallic flange 4^b; then the said flanges are soldered together thus hermetically sealing the joint between the box and the cover. Then the metallic parts which would then show above the bead C³ are covered with cement, as indicated at C² in Fig. 1, thus totally inclosing all the metallic parts in cement and giving the casket the appearance of a sarcophagus; such sarcophagus consisting of a hermetically closed metallic interior portion incased in exterior reinforced concrete; such casket is very durable and capable of preserving bodies therein for an indefinite length of time.

In order to prevent tampering with the contents of the casket when the cover is put thereon, said cover may be provided with depending catches 7 having hook portions 7^a on their lower ends adapted to engage corresponding keepers 7^b attached to the inside of the box as shown in Fig. 2, by which when the cover is placed upon the box it is absolutely fastened, and cannot be removed without actually breaking thereinto.

What we claim is:

1. In a casket, the combination of a metallic box, a cylinder of wire netting attached to said box near the upper edge thereof, wire netting on the exterior of the box below said cylinder, and a concrete layer covering the exterior surfaces of the box below said flange and inclosing said netting and said cylinder, substantially as described.

2. In combination, a metallic box, a me-

tallic flange attached to said box adjacent the upper edge thereof, a cylinder of wire netting attached to said box below said flange, and a coating of concrete covering and inclosing the cylinder and the exterior 70 of the box below said flange.

3. In combination, a metallic box, a metallic flange attached to said box near the upper edge thereof, a wire attached to the exterior of the box below said flange, wire 75 netting attached to the wire, a cylinder of wire netting attached to said box below said flange, a coating of concrete covering and inclosing the wire cylinder, and netting on the exterior of the box below said flange. 80

4. For a casket, a metallic cover having depending sides and ends and an outwardly projecting flange on the lower edges thereof, longitudinally disposed ribs on the upper surface of said cover, transversely disposed ribs within the cover, wire netting extending over said ribs and the top of cover, and a concrete coating inclosing said netting and covering the exterior surface of the top except the said flange. 90

5. In a casket, the combination of a box, a cylinder of netting attached to said box near the upper edge thereof, and netting attached to the exterior of the box below said cylinder, a concrete coating inclosing 95 said cylinder and netting, a cover having a projecting flange on its lower edge, a concrete coating covering the exterior surface of said box, and a concrete seal covering said flanged portions after the cover is placed 100 on the box, substantially as described.

6. In combination, a box, a flange attached to said box near the upper edge thereof, netting attached to the exterior of the box, and a wire cylinder attached to the box below 105 said flange, a coating of concrete covering and inclosing the wire cylinder and netting on the exterior of the box below said flange; a cover having a projecting flange on its lower edge, a concrete coating covering the 110 exterior surfaces of said box but not the flange, and a concrete seal covering said flanged portions after the cover is in place on the box, substantially as described.

7. In a casket, the combination of a metallic box, a cylinder of netting attached to said box near the upper edge thereof, and wire netting attached to the exterior of the box below said cylinder, a concrete coating 115 inclosing said cylinder and netting, a metallic cover having a projecting flange on its lower edge, a reinforced concrete coating covering the exterior surface of said box but not the flange; the flanges of the top and box being soldered together, and a concrete 120 seal covering said flanged portions after they have been soldered together, substantially as described.

8. In combination, a metallic box, a metallic flange attached to said box near the 125

upper edge thereof, a wire attached to the exterior of the box below said flange, wire netting attached to the exterior of the box, and a wire cylinder attached to the box below said flange, a coating of concrete covering and inclosing the wire cylinder and netting on the exterior of the box below said flange but not covering the upper surface of said metallic flange; a metallic cover having a projecting metallic flange on its lower edge, a reinforced concrete coating covering the exterior surfaces of said box but not the flange; the flanges of the top and box being soldered together, and a concrete seal covering said flanged portions after they have 15 been soldered together, substantially as described.

In testimony that we claim the foregoing as our own, we affix our signatures in presence of two witnesses.

LAFAYETTE T. BOW.
DOCTOR B. VERNON.

In presence of—

C. T. VERNON,
W. A. WOLVERTON.
